CLAIM

The ornamental design for a vibrating massager, as shown and described.

DESCRIPTION

FIG. 1 is a front perspective view of a vibrating massager according to our new design;

FIG. 2 is a front view of the vibrating massager of FIG. 1;

FIG. 3 is a rear view of the vibrating massager of FIG. 1;

FIG. 4 is a side view of the vibrating massager of FIG. 1, to which an opposite side view is substantially identical;

FIG. 5 is a top view of the vibrating massager of FIG. 1;

FIG. 6 is a bottom view of the vibrating massager of FIG. 1; and,

FIG. 7 is a rear perspective view of the vibrating massager of FIG. 1.

Elements shown in broken lines show environmental structures of the vibrating massager and form no part of our design.
